DESIGN FOR A MEMO-APPARATUS FOR AUTOMOBILES

Judson R. Otter, Piedmont, W. Va.

Application October 26, 1939, Serial No. 87,875

Term of patent 7 years

To all whom it may concern:

Be it known that I, Judson R. Otter, a citizen of the United States of America, residing at Piedmont, in the county of Mineral and State of West Virginia, have invented a new, original, and ornamental Design for a Memo-Apparatus for Automobiles, of which the following is a specification, reference being had to the accompanying drawing, forming a part thereof.

Figure 1 is a top plan view of a memo-apparatus for automobiles, showing my new design.

Figure 2 is a side view.

Figure 3 is a view illustrating one end of the design.

Figure 4 is a view of the reverse end of the device.

I claim:

The ornamental design for a memo-apparatus for automobiles, as shown.

JUDSON R. OTTER.
